UNITED STATES PATENT OFFICE

139,379

DESIGN FOR A BOTTLE

Eugene Coleman, North Hollywood, Calif.

Application February 5, 1944, Serial No. 112,449

Term of patent 7 years

(Cl. D58—8)

To all whom it may concern:

Be it known that I, Eugene Coleman, a citizen of the United States, residing in the city of North Hollywood, county of Los Angeles, and State of California, have invented a new, original, and ornamental Design for a Bottle, of which the following is a specification, reference being had to the accompanying drawing, forming a part thereof.

The single figure is a front perspective view of a bottle showing my new design. The appearance from the rear is the same as from the front, except that the two bands are plain.

I claim:

The ornamental design for a bottle, as shown and described.

EUGENE COLEMAN.
